FIG. 13

FIG. 14

FIGURE 1 is a perspective view of a hearing aid showing my new design.

FIGURE 2 is a top plan view of the hearing aid of FIGURE 1.

FIGURE 3 is a left side elevational view of the hearing aid of FIGURE 1.

FIGURE 4 is a front elevational view of the hearing aid of FIGURE 1.

FIGURE 5 is a right elevational view of the hearing aid of FIGURE 1.

FIGURE 6 is a rear elevational view of the hearing aid of FIGURE 1.

FIGURE 7 is a bottom plan view of the hearing aid of FIGURE 1.

FIGURE 8 is a perspective view of a second embodiment of the hearing aid of the present invention.

FIGURE 9 is a top plan view of the hearing aid of FIGURE 8.

FIGURE 10 is a left side elevational view of the hearing aid of FIGURE 8.

FIGURE 11 is a front elevational view of the hearing aid of FIGURE 8.

FIGURE 12 is a right elevational view of the hearing aid of FIGURE 8.

FIGURE 13 is a rear elevational view of the hearing aid of FIGURE 8.

FIGURE 14 is a bottom plan view of the hearing aid of FIGURE 8.

This is a continuation of design applications Ser. Nos. D. 11,212 and D. 11,213, filed Mar. 29, 1968 and now abandoned.

I claim:

The ornamental design for a hearing aid, substantially as shown and described.
